UNITED STATES PATENT OFFICE

2,249,829

MANUFACTURE OF NITRIC ACID ESTERS

George E. Hinds, Philadelphia, Pa., assignor to
Sharples Chemicals Inc., a corporation of Delaware

Application October 30, 1939, Serial No. 301,871

7 Claims. (Cl. 260—467)

The present invention pertains to the manufacture of secondary alkyl nitrates, and particularly to the manufacture of alkyl nitrates containing over three carbon atoms.

The esterification of aliphatic alcohols containing three or more carbon atoms has always presented particular difficulties, largely due to the occurrence of side reactions which are difficult to control. In the case of the manufacture of esters by treatment of secondary alcohols with nitric acid, these difficulties have been even more pronounced than in the nitration of primary alcohols, with the consequence that the yields provided by processes heretofore available have been very small.

The object of the present invention has been to afford a process which would have important economic advantages over processes heretofore available for the manufacture of compounds of this character. In the development of a process for accomplishing this object, particular consideration has been given to the following goals:

1. To utilize a cheaper source of raw material than the secondary alcohols, in the esterification operation.
2. To minimize undesired side reactions, and
3. To produce a crude esterification mixture which could be more easily purified than mixtures available from prior art esterification processes.

The first of these goals is accomplished in accordance with the present invention by providing a process in which an olefin may be substituted for the alcohol in the esterification reaction, thereby making it possible to use olefins derived from petroleum, or from other economical sources, as the basis of the secondary alkyl radical.

One of the most serious defects in prior art processes of manufacturing nitric acid esters has been the tendency of the alcohol subjected to esterification to become oxidized to produce the corresponding aldehyde or ketone and products of further oxidation of these compounds. This tendency is reduced in the practice of the present invention, by utilizing the olefin as the source of the alkyl radical. The only danger of ketone formation in the practice of the process of the present invention is involved in the possibility that a small amount of secondary alcohol, formed as a by-product by hydration of the olefin, may be oxidized. Since there is very little of such alcohol present at any stage of the applicant's

process, the formation of ketones is almost completely avoided.

In a co-pending application of John F. Olin et al., Serial No. 240,514, filed November 15, 1938, for Purification of crude esterification mixtures, the difficulties involved in separation of a relatively pure ester from the esterification mixture produced when aliphatic alcohols are esterified by nitric acid are discussed. These difficulties are solved, in the practice of the invention of that application, by a succession of washing steps with water and a base, followed by distillation of the washed mixture. The nitric acid and most of the alcohol are eliminated by the washing steps, and the ester is separated from water and residual alcohol in the distillation steps.

There is very little alcohol in the crude reaction mixture of the present invention, and the separation of the reaction mixture into its constituents can therefore be accomplished with much more facility and efficiency than can the reaction mixture of the above-identified co-pending application.

The invention may be practiced in the manufacture of alkyl nitrates with primary olefins (i. e., straight chain olefins, or branched chain olefins in which the branch does not occur at a carbon atom connected to the double bond), regardless of the carbon content of the particular olefin treated, but it is recommended particularly in connection with treatment of olefins containing between three and nine carbon atoms.

Further objects and advantages of the invention, and the manner in which they have been attained, will be evident from a reading of the following detailed description in the light of the attached flow sheet, in which

The single figure is a diagrammatic illustration of the practice of the invention.

In describing the invention in detail, we shall assume that the olefin to be reacted with nitric acid is pentene-2. This method of description is adopted solely for the purpose of convenience, as the invention is applicable to reaction of various primary olefins containing from two carbon atoms to over nine carbon atoms.

In the practice of the invention, nitric acid is first passed from container 10 to reactor 13. The reactor 13 is equipped with a heating jacket or coil, or with other suitable means for heating the reaction mixture to the best reaction temperature. The nitric acid passed from container 10 to reactor 13 may vary in concentration between 20% and 100%, but nitric acid of between

35 and 65% strength is preferably employed. The strength of nitric acid used in the particular case will depend somewhat upon the reaction temperature and pressure. Thus, if the reaction is accomplished at atmospheric pressure and a temperature of approximately 40° C., the best results are attained by the use of nitric acid of approximately 65% concentration. If, on the other hand, the reaction is conducted at a temperature of 100° C., and about 75 pounds per square inch gauge pressure, acid of approximately 50% concentration is preferred.

After sufficient nitric acid has been passed to the reactor 13 to bring the level of acid in that reactor nearly up to the point from which material is withdrawn from that reactor through valve 15, the reactor is heated to the desired reaction temperature, and pentene-2 (or other primary olefin) is then pumped into the reactor from container 11. At the same time, a small quantity of 50% urea solution may be pumped into the reactor 13 from container 12, in order to cause decomposition of any nitrous acid which may be produced during the course of the reaction.

The mixture in reactor 13 is preferably agitated continuously in order to keep the ingredients thoroughly mixed.

The pentene-2 reacts with the nitric acid in the container 13, in accordance with the following equation:

The reaction mixture passes continuously through the conduit controlled by valve 15, into decanter 14. The pressure in reactor 13 is controlled by control of the valve 15, and is maintained sufficiently high to keep the pentene-2 in the liquid phase.

The mixture collected in the decanter 14 separates into two layers. The heavier layer is dilute nitric acid and a part of this nitric acid is continuously returned through the valve 16 to the reactor 13. As the continuous operation proceeds, it will be desirable either to increase the strength of nitric acid continuously introduced into reactor 13, in order to compensate for dilution of the acid recycled through decanter 14 to the reactor, or to withdraw a part of the nitric acid from the system through valve 17. Nitric acid withdrawn through the valve 17 may be combined with nitric acid derived from other steps of the process, and this nitric acid may be re-concentrated and returned to the container 10 to be used in continued practice of the process. It will be understood that, in the continuous practice of the process, as illustrated in the flow sheet, nitric acid and pentene-2 will be continuously passed to the reactor 13 at approximately the same rate that they are used up in the reaction and withdrawn through valve 15 to decanter 14. Urea solution from tank 12 may also be added to reactor 13 as needed.

The upper layer separated by decanter 14 consists of a solution of unreacted pentene-2, secondary amyl nitrate, and a very small amount of secondary alcohol, formed as a result of hydration of the pentene-2. This upper layer is passed

through a heat exchanger 18, where it is cooled, and is then passed to a mixer 19, in which the constituents of this upper layer are thoroughly mixed with water from container 25. This washing operation, as well as the washing and decanting operations performed in the mixers 19, 21 and 27 and decanters 14, 20 and 22, is performed under slight superatmospheric pressure, in order to minimize losses of pentene-2 by evaporation.

10 The mixture from mixer 19 is next passed to decanter 20. The wash water separates as the heavier phase, and may be combined with dilute nitric acid discharged through valve 17. This combination of aqueous liquids, each containing 15 nitric acid, may be concentrated together, for reuse in the process, or for other appropriate use.

15 The upper (oil) layer from decanter 20 is next passed to mixer 21, where it is thoroughly mixed with an alkaline solution capable of neutralizing 20 the last traces of nitric acid, and effecting further washing of the mixture, (e. g., a 5% soda ash solution). The mixture from mixer 21 is next passed to a decanter 22, in which separation into aqueous and oil phases again occurs. The aqueous phase, containing the alkaline solution, may be returned through valve 23 to mixer 21. It will be necessary, however, to remove alkaline solution periodically from the system through valve 24, and replace it with fresh solution from container 26, in order to maintain the desired strength of alkaline solution.

25 The oil layer from decanter 22 is next passed to a mixer 27, where it is mixed with a further quantity of water from container 25. The resulting mixture is passed to a decanter 28, which operates similarly to decanters 14, 20 and 22, to separate the aqueous wash liquid from the oil phase, which contains the desired secondary amyl nitrate, pentene-2, some water, and a very small 30 trace of secondary amyl alcohol.

35 The washed oil phase, removed as the upper layer from decanter 28, is passed through a heat exchanger 29, where it is heated to a temperature of approximately 80° C. The mixture from 40 heater 29 is passed to a fractionating column 30, which may be operated under a pressure of about 20 pounds per square inch. Pentene-2 and a small amount of water are taken off overhead from this column at a temperature of about 60° C. This overhead mixture is condensed in condenser 31. A part of the condensed mixture is refluxed, and the remainder is passed to a decanter 33, in order to effect separation of the 45 pentene-2, as the upper layer in the decanter, from the water, which forms the lower layer. The pentene-2 separated in this manner from the water may be returned continuously to container 11 for re-use in the process.

50 The temperature in the steam-jacketed still pot 32 is maintained at about 110° C. during the practice of the process. The crude esterification mixture, consisting principally of secondary amyl nitrate, but containing a small quantity of secondary amyl alcohol and water, is continuously 55 drawn off from the still pot 32 to container 34. This esterification mixture may be further purified by distillation, if desired.

60 It will be understood, of course, that wide variations in the above conditions are possible, and that statements as to preferred temperatures, pressures, etc., refer particularly to conditions which are recommended for manufacture of secondary amyl and closely related alkyl nitrates, such as the butyl and hexyl nitrates.

65 Various modifications will be obvious to those

skilled in the art, and I do not therefore wish to be limited except by the scope of the subjoined claims.

As an example of one such modification, it is pointed out that the invention may be practiced by batch operation, instead of by continuous operation as discussed above. The olefin may be reacted with the nitric acid in a batch esterification vessel, for example, and the esterification mixture may then be subjected to the sequence of washing, neutralizing and distilling steps discussed above, or to other steps for purification of the crude ester.

The invention is applicable to the manufacture of cyclo-alkyl nitrates by reaction of cyclo-olefins, such as cyclo-hexene, with nitric acid, as well as to the reaction by which open chain alkyl nitrates are produced.

I claim:

1. The process of manufacturing a secondary alkyl nitrate which comprises heating a mixture of an olefin containing at least three carbon atoms chosen from the class consisting of straight chain olefins and branched chain olefins in which the branch does not occur at a carbon atom connected to the double bond with nitric acid of between 20 and 100% concentration until the olefin reacts with the nitric acid to form the desired alkyl nitrate.

2. The process of manufacturing a secondary alkyl nitrate which comprises heating a mixture of an olefin containing between 3 and 9 carbon atoms and chosen from the class consisting of straight chain olefins and branched chain olefins in which the branch does not occur at a carbon atom connected to the double bond with nitric acid of between 20 and 100% concentration until the olefin reacts with the nitric acid to form the desired alkyl nitrate.

3. The process of manufacturing a secondary alkyl nitrate which comprises heating a mixture of an olefin containing between 4 and 6 carbon atoms and chosen from the class consisting of straight chain olefins and branched chain olefins in which the branch does not occur at a carbon

45

atom connected to the double bond with nitric acid of between 20 and 100% concentration until the olefin reacts with the nitric acid to form the desired alkyl nitrate.

5. The process of manufacturing a secondary alkyl nitrate which comprises heating a mixture of an amylene chosen from the class consisting of straight chain amylenes and branched chain amylenes in which the branch does not occur at a carbon atom connected to the double bond with nitric acid of between 20 and 100% concentration until the amylene reacts with the nitric acid to form the desired alkyl nitrate.

10 6. The process of manufacturing a secondary alkyl nitrate which comprises heating a mixture of an olefin containing at least three carbon atoms chosen from the class consisting of straight chain olefins and branched chain olefins in which the branch does not occur at a carbon atom connected to the double bond with nitric acid of between 35 and 65% concentration until the olefin reacts with the nitric acid to form the desired alkyl nitrate.

15 7. The process of manufacturing a secondary alkyl nitrate which comprises heating a mixture of an olefin containing at least three carbon atoms chosen from the class consisting of straight chain olefins and branched chain olefins in which the branch does not occur at a carbon atom connected to the double bond with nitric acid of between 20 and 100% concentration until the olefin reacts with the nitric acid to form the desired alkyl nitrate.

20 8. The process of manufacturing a secondary alkyl nitrate which comprises heating a mixture of an olefin containing at least three carbon atoms chosen from the class consisting of straight chain olefins and branched chain olefins in which the branch does not occur at a carbon atom connected to the double bond with nitric acid of between 20 and 100% concentration to a temperature above 40° C. until the olefin reacts with the nitric acid to form the desired alkyl nitrate.

25 9. The process of manufacturing a secondary alkyl nitrate which comprises heating a mixture of an olefin containing at least three carbon atoms chosen from the class consisting of straight chain olefins and branched chain olefins in which the branch does not occur at a carbon atom connected to the double bond with nitric acid of between 20 and 100% concentration to a temperature above 40° C. under super-atmospheric pressure until the olefin reacts with the nitric acid to form the desired alkyl nitrate.

GEORGE E. HINDS.
